UNITED STATES PATENT OFFICE.

FRANK E. PHILLIPS, OF HYDEPARK, MASSACHUSETTS.

ELECTRIC-CURRENT REGULATOR.

SPECIFICATION forming part of Letters Patent No. 767,833, dated August 16, 1904.
Application filed April 13, 1904. Serial No. 202,950. (No model.)*To all whom it may concern:*

Be it known that I, FRANK E. PHILLIPS, a citizen of the United States, residing at Hyde-park, in the county of Norfolk and State of 5 Massachusetts, have invented new and useful Improvements in Electric - Current Regulators, of which the following is a specification.

This invention relates to electric - current regulators, the object of the invention being 10 to provide a simple, cheap, and reliable device by means of which a current of any power or intensity may be decreased and regulated to the requirements of electrical appliances requiring a current of smaller or reduced power. By means of the regulator hereinafter described the current may be increased or diminished at will, thus enabling 15 an electric light, for example, to be raised and lowered or to be increased or diminished in 20 its illuminating power in the same manner as an ordinary gas-jet.

With the above and other objects in view the invention consists in the novel construction, combination, and arrangement of parts 25 as herein fully described, illustrated, and claimed.

In the accompanying drawings, Figure 1 is 30 a vertical section through a regulator embodying the present invention. Fig. 2 is a detail section showing the pinion and rack adjustment. Fig. 3 is a detail section showing the ratchet mechanism. Fig. 4 is a diagrammatic elevation showing the manner of introducing the regulator in a circuit.

35 Like reference-numerals designate corresponding parts in all figures of the drawings.

Referring to the drawings, 1 designates a suitable casing, preferably elongated vertically to contain the mechanism hereinafter 40 described, the said casing being closed on all sides and at the top and bottom, any suitable provision being made for giving access to the interior thereof. Within the lower portion of the casing is arranged a liquid-receptacle 45 2, forming what I term a "contact-chamber" 3 and containing a resistance liquid, as shown at 4, and also containing a terminal 5, which is in the form of a contact plate or arch having the end portions thereof in contact with

the outer metallic casing 1, as shown at 6, 50 while the central portion of the plate is preferably arched, as shown, so as to dispose the center thereof at the highest point. Located in the upper central portion of the contact-chamber is another terminal 7, which preferably consists of a German-silver tip or head having a pointed pendent extremity 8 and mounted on and carried by a vertically-extending rack-bar 9, the toothed portion 10 of which cooperates with a pinion 11, which 55 is mounted on a rack-adjusting shaft 12, the latter extending outward through an insulated bushing in the side of the casing, where it is provided with a thumb-wheel 14, by means of which the shaft may be turned for 60 raising and lowering the rack-bar and correspondingly raising and lowering the terminal 7. The rack-bar 9 plays up and down within a housing 15, with which it lies in electrical contact, the contact being insured by the pinion 11, which presses the rack against the 65 back of the housing, as shown in Fig. 2. At its lower end the housing is provided with a sleeve or bushing 16, which passes through an upwardly-extending neck 17 on the liquid-receptacle 2, the latter being preferably 70 formed of glass. At its upper end the housing is flanged, as shown at 18, the flanges extending horizontally and being clamped between the sections of an insulating-bar 19, 75 secured at a suitable elevation within the casing 1.

Electrically connected with one of the flanges 18 is a binding-post 20, through which one of the line-wires 21 is connected, said 80 wire passing through an insulating-bushing 22 in the top of the case. Connected to the lower end of the binding-post 20 is a spring or detent 23, which engages a ratchet-wheel 24, fast on the rack-adjusting shaft 12, hereinabove described, and serves to maintain the ratchet-wheel and its shaft in the position to which they have been adjusted, thus preventing the rack-bar 9 from accidentally descending. Connected to the upper end of the rack-bar 9 is a contact-plate 25, which is adapted 85 to come in contact with the top of the casing 1 when the rack-bar is moved outward. 26

designates a binding-post connected with the top of the casing and adapted to receive the other line-wire 27.

The device as a whole is adapted to be secured to a wall or other support by means of screws or other suitable fasteners 28.

Any suitable liquid 4 may be used for resisting the current passing through the terminals 5 and 7, the nearer together said terminals are adjusted the stronger being the current. In traversing the space between the terminals the liquid acts to resist the current, and thereby reduces the same in strength. Under the adjustment shown in Fig. 1 the current is off. As soon as the point 8 enters the liquid a weak current is established, and as the point is lowered or moved nearer the terminal 5 the strength of the current increases until the terminals meet and the full power of the current is brought into operation, the current passing from wire 27 through binding-post 26, casing 1, terminal 5, resistance liquid 4, terminal 7, rack-bar 9, housing 15, flange 18, binding-post 20, and other wire 21. When the rack-bar is moved upward to its limit, the current passes from wire 27 to binding-post 26, casing 1, contact-plate 25, rack-bar 9, housing 15, flange 18, binding-post 20 to wire 21.

The regulator is simple and extremely durable and after being adjusted is invariable as far as the strength of the current is concerned. The regulator may be placed at any desired point, is perfectly safe, and may be used for reducing a current for any desired purpose and in connection with any suitable

electrical appliances—such as alarm-bells, burglar-alarms, annunciators, lamps, clocks, signals, and, in fact, in any other place where batteries are commonly used. By means of 40 the thumb-wheel 14 lights may be readily raised or lowered and the strength of the current increased or diminished at will.

Having thus described the invention, what is claimed as new is—

45

1. An electric-current regulator comprising a liquid-receptacle, the terminal mounted therein and submerged in the liquid, a second terminal movable within said receptacle, a rack-bar connected with the second terminal, 50 a rack-adjusting shaft, pawl-and-ratchet mechanism for holding said shaft, and binding-posts in electrical communication with the terminals.

2. An electric-current regulator comprising 55 a casing, a liquid-receptacle therein, a terminal submerged in the liquid-receptacle, a second terminal movable toward and away from the first terminal, a rack-bar to which the second terminal is connected, a contact-plate carried by said rack-bar and movable into and out of contact with the casing, a rack-adjusting shaft, and binding-posts, one of which is electrically connected with the casing and the other with the rack-bar.

65

In testimony whereof I affix my signature in presence of two witnesses.

FRANK E. PHILLIPS.
